[57] CLAIM

The ornamental design for wash basins.

DESCRIPTION

FIG. 1 is a top, front, and left side perspective view of wash basins, showing my new design;

FIG. 2 is a perspective view showing the top front and left side thereof;

FIG. 3 is a right side view thereof;

FIG. 4 is a top view thereof;

FIG. 5 is a front view thereof;

FIG. 6 is a bottom view thereof;

FIG. 7 is a top, front, and left side perspective view of a second embodiment, showing my new design;

FIG. 8 is a top view of the two-station wash basin of FIG. 7;

FIG. 9 is a right side view of the wash basin of FIG. 7;

FIG. 10 is a front view of the wash basin of FIG. 7;

FIG. 11 is a bottom view of the wash basin of FIG. 7;

FIG. 12 is a top, front, and left side perspective view of a third embodiment, showing my new design;

FIG. 13 is a top view thereof;

FIG. 14 is a right side view thereof;

FIG. 15 is a front view thereof; and,

FIG. 16 is a bottom view thereof.
